Primary Examiner — Lauren R Calve(74) *Attorney, Agent, or Firm* — Alok Goel(57) **CLAIM**

The ornamental design for a tub for wipes, as shown and described.

DESCRIPTION

FIG. 1 is a top front perspective view of a tub for wipes according to the invention.

FIG. 2 is a top rear perspective view thereof.

FIG. 3 is a bottom front perspective view thereof.

FIG. 4 is a top view thereof.

FIG. 5 is a bottom view thereof.

FIG. 6 is a front side view thereof.

FIG. 7 is a rear side view thereof.

FIG. 8 is a first side view thereof; and,

FIG. 9 is an opposite, second side view thereof.

The broken lines showing environmental structure are for illustrative purposes only and form no part of the claimed design.
